[57] CLAIM

The ornamental design for "a removable cleat for athletic shoes", as shown and described.

DESCRIPTION

FIG. 1 is a perspective view of a removable cleat for athletic shoes, showing my new design;
 FIG. 2 is a front elevational view, the rear, left and right sides being identical thereto;
 FIG. 3 is a bottom plan view thereof;
 FIG. 4 is a top plan view thereof;
 FIG. 5 is a perspective view of a second embodiment;
 FIG. 6 is a front elevational view, the rear, left and right sides being identical thereto;
 FIG. 7 is a bottom plan view thereof; and,
 FIG. 8 is a top plan view thereof.
